UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed November 30, 1923. Serial No. 677,827.

This invention relates to telephone systems and more particularly to connecting circuits for use in extending connections from subscribers' lines terminating in a plurality of 5 connecting terminals.

The object of this invention is to provide a simplified and improved circuit arrangement for permitting a calling subscriber to flash a calling supervisory lamp as a 10 call signal, by the mere act of removing the receiver from the switchhook.

This object is attained in accordance with a feature of the invention by the provision of means for connecting current to a supervisory signal through two parallel paths to 15 actuate the signal in one manner when a calling subscriber hangs up after completing a call, and for intermittently diverting the current around said signal, and through 20 one of the two parallel paths to operate the signal in another manner when the calling subscriber recalls. During the period of 25 conversation between the calling and called subscribers, the supervisory signal circuit is opened so that during this time there is no unnecessary current drain from the battery supply.

In the drawings,

Fig. 1 shows a calling station A and a called 30 station J with associated line circuits, and one of a plurality of connecting or link circuits C, which may be used to interconnect such stations. The station J is one of four 35 stations on the selected line D, the other stations M, W and R being shown schematically.

Fig. 2 shows an operator's telephone set and testing circuit together with party line 40 signaling equipment used in connection with the connecting circuit C.

Each of the stations A and J is shown terminating at a central office in a plurality of answering jacks and a multiple jack. Each answering jack has a signaling device 45 associated therewith. The answering jacks and their associated line lamps for a station terminate at different operators' positions. Multiple jacks, only one of which is shown in the drawings, may appear at each 50 operator's position.

In the following detailed description, it will be first assumed that a subscriber at the station A is the calling subscriber and that a subscriber at a station W, who has

a telephone equipment similar to the one 55 fully shown in station J, is the called subscriber.

Upon initiating a call, the subscriber at station A removes the receiver from the switchhook and establishes an obvious circuit for line relay 3, which relay thereupon operates. Relay 3 in operating, completes a circuit extending from grounded battery, through the filaments of lamps 8 and 9, 60 which lamps are located in front of different operators at the central office, any one of which operators may answer the call. The lamps are illuminated notifying all the operators that a call is awaiting attention.

It will be assumed that at this time, the 70 operator at the position at which lamp 8 is located, is free to handle the incoming call. This operator therefore inserts plug 11 associated with the cord circuit C into jack 12 located at her position and associated with 75 the calling subscriber's line.

Upon the insertion of plug 11 into jack 12, a starting relay 20, common to the link circuits such as C of the operator's position, 80 operates over a circuit extending from ground, through the winding of cut-off relay 4, sleeve contacts of jack 12 and plug 11, winding and contacts 64 of marginal relay 14, contacts 65 of relay 52, conductor 75, contacts 66 of relay 31, contacts 67 of relay 32, winding of relay 20, contacts 68 of relay 35, to grounded battery over the contacts 69 of relay 31. Relays 4 and 14 are marginal and do not receive sufficient current at this 85 time to operate. Relay 20 in operating 90 causes the operation of relay 32, which in attracting its inner left hand armature opens, at the contacts 67, a shunt path normally connected around the polarized relays 30 and 40, connects ground between resistance 95 19 and the winding of relay 20 and at its outer left hand armature connects grounded 100 battery, through resistance 18, between relay 40 and resistance 19. With relay 32 operated, and with ground and grounded battery connected to resistances 19 and 18, as described, a potentiometer circuit arrangement is formed. The closure of contacts 150 of relay 32 causes relay 20 to remain operated through the contact 68 of relay 35 and contacts 69 of relay 31 to grounded battery.

A complete description of the potentiometer circuit just traced and its purpose may

be had by referring to the patent to Fowler No. 1,547,577, issued July 28, 1925.

Since the calling line has been assumed to be free, current will now flow through relays 30 and 40 over conductor 175, in a direction such as to operate relay 30. Relay 40 does not operate at this time because the current flow through its winding is not in the proper direction. The path for operating relay 30 may be traced from ground, through the winding of cut-off relay 4, sleeve contacts of jack 12 and plug 11, winding end contacts 64 of relay 31, windings of relays 30 and 40, contacts 73 of relay 32 and thence through one arm of the potentiometer circuit including resistance 18 to grounded battery. It will be noted that current also flows at this time through resistance 18 and resistance 19 (forming the other arm of the potentiometer circuit) to ground, but this current is ineffectual.

Relay 30 in operating, completes a circuit for relay 31 over a path extending from grounded battery, through the contacts of relay 30, left hand winding of relay 31, to ground at the right hand contacts of relay 32. Relay 31 thereupon operates and locks over a path extending from grounded battery, over the left hand alternate contacts and left hand winding of relay 31, to ground at the right hand contacts of relay 32.

Relay 31 in operating, opens at its contacts 69, the energizing circuit for relay 20, whereupon relay 20 releases, which in turn releases relay 32. Relay 31 in operating, also opens at its contacts 66, the circuit for relay 30, whereupon this relay releases. In attracting its right hand armature, relay 31 connects its right hand winding and resistance 17 in multiple to conductor 75. This circuit is established before the release of relay 32, so that relay 31 remains operated after the release of relay 32. The connection of grounded battery through the right hand winding of relay 31 and resistance 17 in parallel, as hereinbefore mentioned, increases the current flow over conductor 175 sufficiently to permit the operation of marginal relays 4 and 14. Relay 14 in operating, locks over a path extending from ground, through the winding of cut-off relay 4, sleeve contacts of jack 12 and plug 11, winding and contacts 61 of relay 14 to grounded battery. At its armatures 33 and 34, relay 14 connects grounded battery and ground to the ring and tip conductors of the answering end of the links circuit C through the winding of supervisory relay 13, which relay thereupon operates and prevents the operation of relay 101. At its armature 34, relay 14 also connects ground to the conductor 36 leading to the position flashing circuit.

Cut-off relay 4, operating in the circuit above traced, removes the line relay 3 from

the calling line, whereupon this relay releases and opens the circuit for lamps 8 and 9 which thereupon are extinguished.

Relay 22 now operates in a circuit extending from grounded battery, over the armature 33 and front contact of relay 14, conductor 37, winding of relay 22, back contact and right hand armature of relay 85, conductor 38, to ground at the contact 39 of Key 41.

Relay 22 in operating, connects at its armatures 42 and 43, the listening leads from the operator's telephone set to the cord circuit. At its armature 44, relay 22 prepares a circuit for relay 97 in the operator's position equipment and for relay 60. At its armatures 45 and 46, relay 22 connects the common ringing leads to the cord circuit, while at its armature 50 it opens the circuit for relay 101.

The operator's headset being now connected to the cord circuit, the operator may converse with the calling subscriber in order to ascertain the nature of the desired connection. Upon learning that a party on the line D is desired, the operator makes the usual busy test and if the desired line is idle, she inserts the plug 47 of her cord circuit into jack 48 corresponding to the desired line D.

The insertion of plug 47 into jack 48 of the desired line causes relay 52 to operate over an obvious sleeve circuit, which includes the winding of cut-off relay 56. At its right hand armature, relay 52 causes the calling supervisory lamp 49 to be illuminated over an obvious circuit, and also connects battery to the back contact of the tripping relay 84 and to the winding of relay 85. The battery at the back contact of relay 84 causes current to flow through the winding of marginal relay 60 thence over the front contact and armature 44 of relay 22, conductor 54, to ground through the winding of relay 97. Relay 60 does not receive sufficient current at this time to operate. Relay 97, however, operates to cause the pilot lamp 98 to glow in an obvious circuit. At its left hand armature relay 52 opens the original energizing circuit for relay 20 at an additional point.

If the calling subscriber asks for a connection with "party W", the operator actuates key W' for an instant to cause the desired party to be signaled automatically.

The actuation of key W' causes relay 75 to operate. At its contacts 59, relay 75 prepares the peg count relays, 92 and 93 for operation. It may be stated here that the peg count circuit is employed only when a check on the number of calls handled by an operator is to be made. The actuation of key 151 then completes the circuit for these relays and the registering device 152 will be operated whenever a resigning or

trunk key is actuated. At its contacts 57, relay 75 connects ground to the conductor 54, thereby shunting relay 97 and causing the pilot lamp 98 to be extinguished. The current in the circuit including the winding of marginal relay 60 is now sufficient to cause this relay to operate. At its contacts 58 relay 75 causes relay 23 to operate to disconnect the operator's headset from the cord 10 circuit.

Relay 60 in attracting its armature 24, locks under the control of both relays 84 and 52. In attracting its armatures 25 and 26, relay 60 removes the short circuit around 15 the ring-back tone condensers 88 and 89. In attracting its armature 25, relay 60 connects the ground on the outer left hand armature of relay 70 to the tip side of the calling end of the link circuit C. At its armature 27, 20 relay 60 completes the energizing circuit for the winding of relay 85, which was initiated by the operation of relay 52.

With relays 85 and 60 operated, a circuit for a special code of ringing current is established which may be traced from the ringing source 130 (Fig. 2), through the interrupter 28, conductor 29, contacts 62 of relay 63, winding of marginal relay 84, front contact and left hand armature of relay 85, 30 outer right hand armature and back contact of relay 70, front contact and armature 26 of relay 60, ring contacts of plug 47 and jack 48, and thence through the bells at the subscriber's station W, to ground. The 35 condensers 88 and 89 serve to complete a path back to the calling subscriber's line, thereby enabling the calling subscriber to hear the ringing signal.

Should the "party R" be desired by the 40 calling subscriber, the operator would momentarily actuate key R', whereupon relay 74, operates. At its contacts 77, relay 74 causes relay 63 to operate in a circuit extending from grounded battery, over the right hand armature and front contact of relay 52, back contact and armature of tripping relay 84, winding of relay 63, conductor 71, front contact and armature 46 of relay 22, conductor 78 to ground at the 45 contacts 77 of relay 74. At its contacts 78, relay 74 causes relay 75 to operate causing a closure of the peg count circuit, the shunting of relay 97, the extinguishment of lamp 98 and the operation of relays 60 and 23 as 50 hereinbefore described.

Relay 63 in attracting its armature 79, locks up under the control of relays 84 and 52. At its armature 82, relay 63, prepares a circuit for relay 83 and at its contact 86 55 prepares the connection of lead 87 from the ringing current supply to the ring side of the cord circuit.

At the proper interval, battery from the ringing equipment will be connected to lead 60 90 through the interrupter 91, whereupon

relay 83 operates in a circuit extending from grounded battery on the lead 90, normal make-before-break contacts of relay 83, winding of relay 83, armature 82 and front contact of relay 63 to ground. Relay 83 in attracting its outer armature locks up over an obvious circuit. At its inner armature, relay 83 causes a special current code to be connected to the ring side of the cord. This path may be traced from the ringing current source 130 (Fig. 2) through the interrupter 94, conductor 87, front contact and inner armature of relay 83, contacts 86 of relay 63, winding of tripping relay 84, front contact and inner left hand armature of relay 85, conductor 67, outer right hand armature and back contact of relay 70, front contact and armature 26 of relay 60, ring contacts of plug 47 and jack 48, and thence through the bells at the subscriber's station 85 R, to ground.

If the operator receives a request for "party J", she momentarily actuates the corresponding key J', whereupon relay 73 operates to cause relay 75 to operate. The latter 90 in operating, performs the same functions as in the previous connection. At its contacts 96, relay 73 connects ground to the conductor 99, causing relay 70 to operate in a circuit extending from grounded battery, 95 over the right hand armature and front contact of relay 52, back contact and armature of relay 84, right hand winding of relay 70, front contact and armature 45 of relay 22, conductor 99 to ground at the contact 96 of 100 relay 73.

Relay 70 at its outer left hand armature, connects ground to the ring side of the cord circuit C by way of the front contact and armature 26 of relay 60. At its inner left hand armature, relay 70 locks through its left hand winding. At its outer right hand winding, relay 70 prepares a circuit for transmitting ringing current over the tip side of the cord and at its inner right hand armature, establishes an energizing circuit for the right hand winding of relay 85 to grounded battery on the front contact and right hand armature of relay 52. After an interval, slow operating relay 85 operates and locks to ground on the normal contact 39 of key 41. At its left hand armature, relay 85 completes the circuit to the tip conductor of the cord circuit initiated by relay 70 at its outer right hand armature. 125

Ringing current from the source 130 now passes through interrupter 28 over conductor 29, contacts 62 of relay 63, winding of tripping relay 84, front contact and inner left hand armature of relay 85, conductor 67, outer right hand armature and front contact of relay 70, front contact and armature 25 of relay 60, tip contacts of plug 47 and jack 48 and thence through the bells at the subscriber's station J to ground. 130

To signal the party M, the operator actuates key M' causing relay 72 to operate. Relay 72 in operating, causes both relays 73 and 74 to operate, which in turn cause relay 75 to operate. The operating circuits for relays 73, 74 and 75 are obvious. Relays 73, 74 and 75 in operating perform the same functions hereinbefore described in connection with the actuation of keys J, R, 10 and W, respectively, and it is believed unnecessary to repeat them.

At the proper interval, battery will be connected to the conductor 90 by way of interrupter 91, whereupon relay 83 operates to ground on the front contact and armature 82 of relay 63. Relay 83 in operating, locks under the control of relay 63.

The circuit for ringing current may now be traced from the ringing current supply, 20 through interrupter 94, conductor 87, front contact and inner armature of relay 83, contacts 86 of relay 63, winding of tripping relay 84, front contact and inner right hand armature of relay 85, outer right hand armature and front contact of relay 70, front contact and armature 25 of relay 60, tip contacts of plug 47 and jack 48 and thence through the bells at the subscriber's station M, to ground.

30 From the descriptions of the signaling of the various parties on a line, it is apparent that the tip conductor of the cord is employed in signaling two of the parties and the ring conductor for the other two, and 35 that each party has a special ringing code.

Should the operator neglect to depress the ringing key such as keys M', J', R' or W' for a sufficient length of time or to a sufficient extent, the ringing pilot lamp 98 will remain lighted since relay 97 will not have been shunted down. Upon noting the continued illumination of lamp 98, the operator will know that the ringing equipment has not functioned and she will again actuate the proper key.

40 In each of the preceding ringing operations, relay 85 in operating, after an interval, opens the circuit for relay 22, which in releasing disconnects the operator's telephone set and the common ringing equipment from the cord circuit. It will also be noted that although ringing current in each instance passes through the winding of tripping relay 84, this relay is marginal and 45 does not operate until the called subscriber responds to the signal.

When the called party answers the signal, the tripping relay 84 operates and opens the locking circuits for relays 60, 70 and 60 63 releasing them, if operated. The operation of relay 84 is effected in the following manner: When the subscriber such as party J removes the receiver from the switchhook, the condenser 155 is short circuited by the switchhook contacts, thereby

reducing the resistance of the circuit including relay 84 to such an extent as to permit this relay to operate, it being understood that ground is applied to the tip or ring conductor of the cord depending on whether 70 the ringing current is applied to the ring or tip of the cord. This ground serves as a return path for the ringing current when the subscriber removes the receiver. The release of relay 63 causes relay 83 to restore. 75 Relay 60 in restoring again shunts the ring back tone condensers 88 and 89, and renders the tip and ring conductors of the calling end of the link circuit C continuous. Upon the release of the armatures 26 and 24 of 80 relay 60, the calling supervisory relay 100 operates in an obvious circuit from battery associated with the repeating coil 15, over the closed called subscriber's line loop. Relay 100 in operating, causes lamp 48 to be 85 extinguished.

Should the called subscriber at any time desire to flash the operator, he may do so by actuating his switchhook thereby causing relay 100 to intermittently deenergize and 90 energize, whereupon the lamp 49 flashes in synchronism with the switchhook actuations.

At the termination of the conversation, the called subscriber on restoring his receiver causes relay 100 to restore whereupon lamp 49 glows steadily serving as a disconnect signal to the operator.

When the calling subscriber hangs up his receiver, answering supervisory relay 13 releases, whereupon relay 101 operates in a 100 circuit extending from grounded battery, over the armature 33 and front contact of relay 14, back contact and armature of supervisory relay 13, normal make-before-break contacts and winding of relay 101, 105 back contact and armature 50 of relay 22 to ground at the contact 102 of key 41. Relay 101 in operating locks over a path including its contacts 140, back contact and armature 50 of relay 22, and contacts 102 of 110 key 41. Relay 101 in operating causes the lamp 55 to be lighted over two parallel paths, one extending from grounded battery, contacts 140 and 103 of relay 101, resistance element 104, filament of lamp 55 to 115 ground on the contacts 105 of relay 14, and the other, from grounded battery, armature 33 and front contact of relay 14, back contact and armature of relay 13, front contact and inner right hand armature of relay 101, resistance element 106, filament of lamp 55 to ground on the contacts 105 of relay 14. The steady glow of lamp 55 indicates to the operator that the calling subscriber has replaced the receiver on the switchhook.

Should the calling party desire to recall the operator before the operator takes down the connection he will merely remove the receiver from the switchhook whereupon relay 13 reoperates over the subscriber's line loop.

Relay 13 in operating at this time, connects the resistance element 106 in multiple with lamp 55, to the conductor 111 to cause the flashing of the lamp 55. This flashing is effected in the following manner. When relay 14 first operated, as a result of the insertion of plug 11 into jack 12, it caused relay 107 (Fig. 2), to operate in a circuit extending from grounded battery, through the winding of relay 107, conductor 36, and contacts 105 of relay 14 to ground. Relay 107 in operating, connects the interrupter 110, to the winding of relay 108 causing this relay to be intermittently operated. Relay 108 in operating, intermittently connects ground through the winding of relay 109, over conductor 111 to the outer right hand armature of relay 101. Therefore, with relay 101 operated and when relay 13 reoperates, the battery associated with armature 33 of relay 14 is disconnected from the lamp 55 at the back contacts of relay 13 and the greater portion of the current from the battery associated with the left hand armature of relay 101 passes over the contacts 140 and 103 of relay 101, resistances 104 and 106, inner right hand armature of relay 101, armature and front contact of relay 13, front contact and outer right hand armature of relay 101, conductor 111, armature and front contact of relay 108 to ground through the winding of relay 109, when relay 108 is operated. It is therefore apparent that each time relay 108 operates the lamp 55 is shunted and relay 109 operated. The lamp 55 is accordingly flashed and relay 109 operated in synchronism with the operations of relay 108. The pilot buzzer 155 is thereby operated to give an audible recall signal.

Upon the receipt of this flashing signal, the operator may remove plug 47 from the jack 48 of the called subscriber's line or may actuate key 112. The first operation causes the release of relay 52, which opens the locking circuit for relay 85. Relay 85 in releasing its right hand armature, causes relay 22 to be reoperated from battery associated with the armature 33 of relay 14. Relay 22, in reoperating opens at its armature 50 and back contact, the locking circuit for relay 101, which thereupon releases and stops the flashing of lamp 55. The actuation of key 112 also opens the locking set of relay 101 and bridges the operator's telephone set across the link circuit C.

If the plug 47 had already been removed from jack 48, relay 85 would be released so that relay 22 would be reoperated. The locking circuit for relay 101 would, therefore, be opened at the armature 50 of relay 22, so that the lamp 55 would not be flashed under such a condition. It will be noted that under such a condition, when relay 22 releases the operator's head set is connected across the cord and the calling subscriber

may converse with the operator without the flashing signal.

When, at the termination of the conversation (assuming plug 47 to be still connected with jack 48), the operator removes plug 11 from jack 12, relays 14 and 4 restore, the latter again associating the line relay 3 with the line A. Relay 14 in retracting its armature 33, opens the circuit for relay 22 which releases. When the operator removes the calling plug 47 from jack 48, relay 52 will release causing the lamp 49 to be extinguished and restoring the link circuit C to normal.

On a connection over a trunk circuit, wherein ringing current is not essential to the establishment of a connection the operator having access to the link circuit C, after having inserted the plugs 11 and 47 into the jack 12 and the jack of the outgoing trunk circuit respectively, depresses the trunk key T. Upon the connection of the link circuit with the calling line and the outgoing trunk, the same link circuit apparatus will function as hereinbefore described in connection with extending a call from a calling subscriber to a called subscriber by way of the link circuit only. When the trunk key T is actuated, relay 76 operates, and at its contact 110 causes the peg count equipment to function as in the previous connection. At its contacts 111, relay 76 connects ground to the conductor 99 which causes relay 70 to operate in a circuit extending from grounded battery, over the armature and front contact of relay 52, back contact and armature of relay 84, right hand winding of relay 70, front contact and armature 45 of relay 22 to the grounded conductor 99. Relay 70 operates in this circuit and locks through its left hand winding and inner left hand contacts to ground, thereby removing its control from relay 22.

Unless relay 60 is operated, relay 70 performs no ringing function. At its inner right hand armature, relay 70 causes relay 85 to operate in an obvious circuit. Relay 85 locks under the control of key 41 and opens the circuit for relay 22 which thereupon releases causing the disconnection of the common ringing and listening equipment from the link circuit. It is therefore apparent that by the actuation of the trunk key T on a trunk connection, which corresponds to the actuation of a ringing key on a subscriber to subscriber connection, the ringing equipment associated with the link circuit is prevented from functioning to send out ringing current over the connection.

Should the calling subscriber on initiating a call make a request for another party on the same line, the operator will instruct him to replace his receiver on the switchhook for a minute. When the operator hears the disconnect click which accompanies the res-

10 toration of the receiver by the calling subscriber, she removes the plug 11 from the answering jack and replaces it with the calling plug 47. Upon the insertion of plug 47 into jack 12, relay 52 operates in an obvious sleeve circuit causing relay 22 to operate to connect the common ringing and listening equipment to the link circuit. The operator then actuates the key corresponding to the party desired, to initiate the ringing signal. When the ringing of the called party starts, relay 22 releases as hereinbefore described to remove the common ringing and listening equipment from the link circuit. Should 15 the calling party come back on the connection too soon, that is, before the called party has answered the signal, the removal of the receiver by the calling party would trip the ringing current as hereinbefore mentioned 20 and would cause lamp 49 to light. The operator then actuates key 112 to connect her headset to the link circuit and requests the calling subscriber to replace his receiver on the switchhook and wait for a short period 25 of time. The operator then again initiates the ringing of the desired party, by actuating the corresponding key.

Having described in detail the arrangement of a connection between a subscriber at 30 station A and a subscriber at station B, it will now be assumed that the operator at which jack 12 and its associated line lamp 8 appears, has answered a call from the subscriber at station A and that an operator at 35 the position at which lamp 9 is located attempts to handle the call upon noting the illumination of lamp 9. It is to be understood that the operator at such position attempts to handle an incoming line immediately after the first operator has answered 40 a call, otherwise the lamp 9 would have been extinguished shortly after the insertion of plug 11 into jack 12.

The second operator having a cord and 45 associated test and operator's circuit identical with the one shown in the drawings, inserts plug 11 thereof into jack 50. The sleeve of jack 50 being multiplied with that of jack 12, now has a busy potential connected thereto owing to the insertion of plug 11 of the original cord circuit into jack 12 by the first operator. The potential on the sleeve of jack 12 has been provided from the battery associated with the sleeve of the plug 50 of the original cord circuit.

Upon the insertion of plug 11 of the second cord circuit into jack 50, an energizing circuit is established for relay 20 over a path extending from ground through the 60 winding of cut-off relay 4, sleeve of jack 50 and sleeve 11, winding and contacts 64 of relay 14, contacts 65 of relay 33 contacts 66 of relay 31, contacts 67 of relay 32 winding of relay 20, contacts 68 of relay 35, 65 and contacts 69 of relay 31, to grounded

battery. (The apparatus above mentioned is associated with the second operator's equipment). Another path for current through the winding of relay 4 to ground, extends through the sleeves of jack 12 and plug 11, the winding of relay 14, to battery potential, but relay 20 of the second operator's equipment is of the sensitive type and operates in the parallel branch to battery extending to the second cord. Relay 20 70 of the second operator's equipment in operating, causes the operation of relay 32 which closes at its contacts 73, the circuit previously traced for holding relay 20 operated. Due to the fact that a plug at another operator's 75 position has been previously inserted into a multiple of the jack 50, the current flowing through the polarized relays 30 and 40 is in a direction opposite to that which it was when the line was idle, and is in such a direction as to cause the operation of polarized relay 40 only. The reason that the current flows in a reverse direction at this time is due to the fact that an unbalanced Wheatstone bridge arrangement is formed. A 80 complete discussion of this current reversal at this time may be had by referring to the above identified copending application. 85

The operation of polarized relay 40 associated with the second connected cord circuit, causes the operation of relay 35 and establishes a holding circuit for relay 32 through the right hand winding thereof. Relay 35 in operating, releases relay 20 and 90 opens contacts in the leads from the operator's telephone set extending through the listening key 112 of the second connected cord circuit and the listening keys of the other cord circuits at the same operator's position. In closing its alternate contacts, 95 relay 35 connects a source of tone supply 80 to the receiver 81 to indicate to the operator the busy condition of the calling line, or the fact that the call has already been answered by another operator. 100

The operator noting the tone signal removes the plug 11 of the second operator's link circuit from jack 50, whereupon relay 40 releases. Relay 40 in retracting its armature opens the holding circuit for relay 32 105 which relay then releases. Relay 35 also releases as a consequence of the release of relay 40 and being of the slow-to-release type retracts its armature at an interval after its energizing circuit is opened at the contacts of relay 40. Relay 35 in restoring restores the operator's telephone to 110 normal.

The invention claimed is:

1. In a telephone system, a telephone line, 115 a link circuit, a signal for the link circuit, a source of current, means for first connecting current from said source to said signal to actuate said signal when the subscriber of said line hangs up after completing a call, 120 125

and means for intermittently shunting said signal to flash said signal when the subscriber of said line recalls.

2. In a telephone system, a telephone line, 5 a link circuit, a signal for the link circuit, a source of current, and means for first connecting current from said source to said signal to actuate said signal when the subscriber of said line hangs up after completing 10 a call and for intermittently diverting a portion of said current around said signal to flash said signal when a subscriber of said line recalls.

3. In a telephone system, a telephone line, 15 a link circuit, a signal for the link circuit, a source of current, means for first connecting current from said source to said signal to actuate said signal when the subscriber of said line hangs up after completing a 20 call, and means for intermittently diverting a portion of said current around said signal to flash said signal when the subscriber of said line recalls.

4. In a telephone system, a telephone line, 25 a link circuit, a source of current, means including a supervisory relay for first connecting current from said source to said signal to actuate said signal when the subscriber of said line hangs up after completing 30 a call, and interrupter mechanism for intermittently diverting a portion of said current from said source around said signal to flash said signal when a subscriber of said line recalls.

5. In a telephone system, a telephone line, 35 a link circuit, a source of current, means including a supervisory relay for first connecting current from said source to said signal to actuate said signal when the subscriber of said line hangs up after completing a call, and interrupter mechanism for intermittently diverting a portion of said current around said signal to flash said signal when a subscriber of said line recalls, said interrupter mechanism being conditioned for 40 operation when said link circuit is connected to said telephone line.

6. In a telephone system, calling and 50 called subscribers' lines, a link circuit, a signaling device associated with the link circuit, interrupter mechanism, a sleeve relay for the link circuit, an operator's telephone set, means controlled by said sleeve relay for connecting the operator's telephone set to 55 the link circuit, a relay operated in response to the actuation of the sleeve relay for preparing the interrupter mechanism for operative relationship with the signaling device, a circuit completed for the signaling device 60 when the calling subscriber hangs up, for steadily actuating said signal device, and circuit connections for connecting said interrupter mechanism in operative relationship with said lamp to flash said lamp when the 65 calling subscriber recalls.

7. In a telephone system, a telephone line, a link circuit connected thereto, a supervisory relay for the link circuit, a locking relay operated upon the deenergization of the supervisory relay, a signaling device, an 70 operating circuit therefor including contacts of said supervisory relay and said locking relay established upon the deenergization of said supervisory relay, interrupter mechanism, and another circuit completed to control the flashing of said signaling device upon the subsequent energization of said supervisory relay, including contacts of said supervisory relay and said second relay. 75

8. In a telephone system, a telephone line, 80 a link circuit connected therewith having an answering and a calling end, a signaling device, a supervisory relay for said link circuit controlled over the answering end of said link circuit, a locking relay operated 85 in response to the deenergization of said supervisory relay to effect a circuit for said signaling device, whereby said signaling device is actuated, a shunt circuit for said signaling device prepared by the operation 90 of said locking relay and completed by a subsequent operation of said supervisory relay, means for intermittently connecting said shunt circuit about said signaling device to cause said signaling device to be intermittently operated, a key, and means controlled by said key and the calling end of 95 said link circuit for restoring said locking relay to normal, thereby stopping the intermittent operation of said signaling device. 100

9. In a telephone system, calling and called subscribers' lines, a connecting circuit interconnecting said lines, a supervisory signal, a key, an operator's telephone set, means responsive to a disconnection by the calling subscriber to actuate said supervisory signal in one manner, said means being also responsive to the initiation of a recall signal by the calling subscriber to actuate said signal in another manner, and means responsive to the actuation of said key for deenergizing said signal and bridging said telephone set across said connecting circuit, said means also responsive to the disconnection of 110 said connecting circuit from said called subscriber's line. 115

10. In a telephone system, the combination with a telephone line of a substation switch, a supervisory lamp, a circuit for said lamp including two parallel branches completed upon the actuation of said substation switch, and means responsive to a single subsequent actuation of said substation switch for intermittently connecting one of 120 said parallel branches in shunt of said lamp, causing the same to be flashed. 125

11. In a telephone system, a telephone line, a connecting circuit associated therewith, a supervisory signal, a circuit for said 130

- signal including two parallel branches established upon the disconnection by the subscriber of said line to cause a steady operation of said signal, and means responsive to the initiation in a recall signal by the subscriber of said line for intermittently connecting said parallel branches in series relation with each other to cause the flashing of said signal.
- 10 12. In a telephone system, a telephone line, a connecting circuit associated therewith, a supervisory lamp, means responsive

to a disconnection by the subscriber of said line for establishing a circuit including the filament of said lamp in series with two parallel branch circuits, and means responsive to a recall by the subscriber of said line for intermittently connecting said two branch circuits, in series with each other and one thereof in shunt of said lamp.

In witness whereof, I hereunto subscribe my name this 27th day of November A. D., 1923.

CLARENCE B. FOWLER.
